E. CAHOW

GAS CONTROL VALVE

Filed Sept. 1, 1923

INVENTOR.
Ervin Cahow
BY
Edward N. Pagelum
ATTORNEY

UNITED STATES PATENT OFFICE.

ERVIN CAHOW, OF DETROIT, MICHIGAN.

GAS-CONTROL VALVE.

Application filed September 1, 1923. Serial No. 660,521.

To all whom it may concern:

Be it known that I, ERVIN CAHOW, a citizen of the United States, and residing at Detroit, in the county of Wayne and 5 State of Michigan, have invented a new and Improved Gas-Control Valve, of which the following is a specification.

This invention relates to means for closing the fuel-control valves of gas burners 10 whenever the supply fails and whenever the flame is discontinued for any other reason, and its object is to provide a device of this character which shall be entirely automatic in its action, which shall be simple and reliable, and which can be produced at low 15 cost.

This invention consists in a control valve 20 for gas-burners embodying a valve seat, a valve and a spring to hold it on its seat, and means connected to said valve by means of which said valve may be held away from its seat and which releases said valve whenever the valve is moved farther from its seat.

25 It further consists in combination with a valve of this character, of an actuating member affected by the temperature of the space around or adjacent the burner, which member when thus affected opens the valve 30 still farther and permits the valve-opening means to return to its normal inoperative position.

It also consists in the details of construction 35 illustrated in the accompanying drawing and particularly pointed out in the claims.

In the drawing, Fig. 1 is an elevation of 40 a water-heater equipped with my improved control valve. Fig. 2 is a longitudinal section of the valve. Fig. 3 is an elevation of the upper part thereof.

Similar reference characters refer to like parts throughout the several views.

Many serious accidents have been caused 45 by the ignition of bodies of gas which have escaped from gas-burners after the flame thereof has been extinguished because of a temporary failure of the gas supply or because of a defect in the mechanism or for 50 other reasons. The present invention is designed to close the gas passage to the burner when the flame is extinguished and to prevent a renewal of such flow until a movable member is manually shifted to reopen such 55 gas passage.

The valve body 1 has a diaphragm or partition 2 provided with a passage 3 adapted to be closed by the valve 4, which may be of any desired construction. A plug or cover 5 is bored to receive the slidable stem 60 6 normally held down by the spring 7. A pin 8 on the stem 6 is the pivot of a cam 9 provided with a seat 10 so that when the cam is swung to the position shown in dotted lines in Fig. 2, the stem 6 and valve 65 4 are elevated to move the valve from its seat. This cam engages the nut 11 of the stuffing box at the top of the plug 5. A handle 12 is provided to operate this cam to lift the valve 4 to the position shown in 70 dotted lines in Fig. 2.

The heater shown in Fig. 1 is of well known construction and is merely shown as an embodiment of this invention. A shell 14 encloses a water-coil 15 and ring burner 75 16 which receives gas from the pipe 17 connected to the control valve 1. Within the coil or at any other desirable or convenient location, is a thermostat, preferably a bar 18 which expands at a higher rate than the 80 shell 14. A pin 19 on the top of the shell is the fulcrum of the lever 20 and the thermostat bar 18 extends from the seat 22 of the lever 20 and raises its outer end 23 whenever fuel gas is ignited at the burner 16. 85

The free end of the lever is perforated to receive the rod 24 which constitutes an extension of the stem 6, the upper end of this rod being threaded to receive the nut 25. The operation of this device is as follows. When the burner is to be used, the handle 12 is swung to the position shown in dotted lines in Fig. 2 to open the valve and the gas is ignited. Nothing further is required. As soon as the bar 18 becomes 95 sufficiently hot and expands, it swings up this lever 20 which engages the nut 25 and lifts the stem 6 still farther, sufficiently to free the cam 9 and permit the handle 12 to swing to horizontal position. 100

The temperature of the bar 18 at which it lifts the stem 6 is determined by the nut 25 on the rod 24 which may be screwed up or down to adjust this device for higher or lower temperatures, for it is evident that 105 as the lever 20 swings with this bar and according to its temperature, the normal space between the free end of this lever and the nut will determine how many degrees the bar 18 may increase in heat be- 110

fore the stem 6 is lifted to release the handle 12.

As soon as the flame is extinguished, the bar 18 cools and contracts, permitting the 5 lever 20 to swing down under the pull of the spring 7 and the valve 4 to be forced down by the spring to close the passage 3. The passage then remains closed until the 10 handle 12 is again swung up manually to 10 the dotted line position.

The details of construction and the proportions of the parts may all be changed by those skilled in the art without departing from the spirit of my invention as set 15 forth in the following claims.

I claim:—

1. In combination with a pipe, a valve in said pipe, means to close the valve, a cam adapted to be moved to open the valve 20 against the force of said valve closing means said cam being held from turning by said force, and a thermostat to release said cam from said force so said cam may return to normal position.
2. In combination with the supply pipe 25 of a gas-burner, a valve in said pipe, a spring to close the valve, a cam to open the valve against the force of the spring and having a flat side adapted to bear 30 against a portion of the valve and be held

therefrom from turning by the force of said spring, a thermostat to release said cam from the force of said spring, and means attached to said cam to move it to normal position.

3. In combination with the supply pipe of a gas-burner, a valve to control the flow of gas to the burner, and a stem connected thereto, manually operable means operatively connected to said stem to move the 40 stem to open the valve a predetermined distance and hold it in such position, a thermostat to move the stem still farther and release it from said manually operable means when the effect of the heat of the burner 45 on the thermostat reaches a predetermined degree and to hold the valve open, and an adjustable connection between the thermostat and stem to determine such degree.

4. In combination with a supply pipe, a 50 valve in said pipe, a stem connected to the valve, manually operable means operatively connected to said stem to move the stem to open the valve a predetermined distance and hold it in such position, and a thermostat to move the stem still farther and release it from said manually operable means and to hold the valve open when it reaches a predetermined temperature.

ERVIN CAHOW.
